CARTON

Ersel C. Mulnix, Lake Bluff, Ill.

Application October 14, 1948, Serial No. 54,457

4 Claims. (Cl. 229—39)

1

This invention relates to an improvement in cartons, and more particularly to an improvement in bottle-carrying cartons, although cartons embodying the invention may be employed for carrying goods other than bottled goods.

The principal objects of the invention are to provide a carton of very rigid and durable construction, but which may be quickly and easily manually set up or formed from a collapsed blank; to provide such a carton having a very strong bottom construction so as to be especially adapted to the carrying of heavy goods such as bottled goods; to provide a carton of the character indicated having a bottom construction which will withstand the effects of moisture to which the bottom may be subjected incident to the packaging of cold bottled goods in the carton and the condensation of moisture on the cold walls of the bottles; to provide a carton which will firmly hold bottles therein in tightly packed condition so as to prevent rattling of the bottles within the carton; to provide an efficient carton of the character indicated which will completely enclose the goods, and which will be easy to close, and which will effectively remain closed without employment of adhesives or various forms of locking tabs; and to provide a carton of the character indicated with a carrying handle arrangement which may be quickly and easily applied as a step in the process of packaging goods in the carton and closing the same, and which handle may be adjusted to an out-of-the-way position when desired, especially for packaging the filled cartons in other containers.

In general, it is the object of the invention to provide an improved carton of the character indicated, and other objects and advantages of the invention will be understood by reference to the following specification and accompanying drawings (4 sheets) in which there is illustrated a carton embodying a selected form of the invention.

In the drawings:

Fig. 1 is a perspective illustrating a completed and closed package comprising the improved carton.

Fig. 2 is a plan view of a blank from which the improved carton is formed.

Figs. 3 and 4 are perspective illustrations of the bottom construction of the carton, these views showing successive steps in the closing of the bottom.

Fig. 5 shows the bottom of the carton in its closed condition.

Figs. 6 and 7 are sections respectively on planes represented by the lines 6—6 and 7—7 of Figs. 1 and 5.

Fig. 8 is a plan view illustrating the carton after it is filled with bottled goods, but before the carton is closed, and

2

Figs. 9 and 10 are perspective illustrations showing successive steps involved in the closing of the carton and the application of a carrying handle thereto.

5 The improved carton herein illustrated is of generally rectangular form embodying opposite end wall panels 1 and 2, and side wall panels 3 and 4. These side wall panels embody upper and lower sections respectively designated 1a and 1b, 2a and 2b, etc., the sections being separated from each other by substantially straight horizontally extending fold lines 5 and 6 in the side walls 3 and 4, and horizontally extending curved fold lines 7 and 8, respectively, in the end walls 1 and 2. The side wall panel 3 is provided with a glue flap extension 9 which is adhesively attached to the free margin of the end wall panel 2 to form the blank into a tube which may be collapsed to flat form as is well known in the art of box making.

10 The end walls 1 and 2 are equipped with bottom-forming flaps 10 and 11, respectively, which are of length and breadth substantially corresponding to the length and breadth of the set-up carton so that each flap extends over the entire bottom area of the carton.

15 The side walls 3 and 4 are provided with bottom-forming flaps 12 and 13, respectively, these flaps being so formed that they are adapted to cooperatively form another bottom wall ply.

20 By reference to Figs. 3, 4, and 5, it will be seen that the flaps 10, 11, 12, and 13 are folded into bottom-forming position by first folding the flaps 10 and 11 over the end area of the tubular carton body, the preglued blank being, of course, first squared up to the desired tubular form. Then, the flaps 12 and 13 are folded inwardly into outwardly overlapping relation to the flaps 10 and 11.

25 The flaps 12 and 13 are of generally rectangular form except that they each have corner portions cut out so as to form, in effect, reduced width portions 12a and 13a, respectively, which, at their junctions with the main bodies of the respective flaps 12 and 13, are of substantially one-half the horizontal dimension of the length of the carton walls with which said flaps are associated.

30 This arrangement permits the flaps 12 and 13 to more or less intermesh in the flat, fully folded condition illustrated in Fig. 5 wherein in said flaps 12 and 13 and their respective portions 12a and 13a cooperate to form a third bottom wall over the entire area of the carton, portions of the said third bottom wall being of double thickness, i. e., where the flap portion 12a overlaps the flap body 13 and where the flap portion 13a overlaps the flap body 12.

35 The bottom-forming flaps 12 and 13 are locked in closed position by means of tongues 14 and 15, respectively, which are formed integrally with the said bottom flaps being connected thereto

by extension panels 12b and 13b, respectively. The extension panels 12b and 13b are foldably connected to the respective flap portions 12a and 13a by means of wide fold line areas 16 and 17, respectively, and the tongues 14 and 15 are foldably connected to said panels 12b and 13b, respectively, by means of suitable fold lines 18 and 19. The tongues 14 and 15 have end ears 14a for the tongue 14, and 15a for the tongue 15, such end ears being provided at both ends of the tongues.

These locking tongues are employed by bending the panels 12b and 13b over the lower marginal portions of the side walls 4 and 3, respectively, and tucking the tongues 14 and 15 inwardly through openings 20 and 21 provided in the walls 4 and 3 by the displacement of ears 3c and 4c, respectively. The ears 3c and 4c are provided for by suitable slits 22 and fold lines 23 which permit the ears 3c and 4c to be displaced from the respective walls by being bent inwardly therefrom. The tongues 14 and 15 are longer than the openings 20 and 21 by an amount approximately corresponding to the total length of the tongue end ears 14a and 15a, respectively, so that when the tongues are forced inwardly through the respective openings 20 and 21, the end ears on said tongues will necessarily be bent back to permit the tongues to pass through the openings. The normal resiliency and flexibility of paper-board, such as employed in the making of cartons of this type, readily permits the ears to be so bent back, and will cause the ears to more or less resume their normal co-planar relation to the bodies of the tongues from which they extend.

While these locking tongues need not be folded to flat, face-to-face position on the inner faces of the side walls of the carton, they may be so proportioned that when folded to face-to-face condition as best shown in Fig. 7, the free ends of the tongues may be caused to extend between the opposite edges of one or both of the inner bottom flaps 10 and 11 and the adjacent side wall 3 or 4. This locking of the locking tongues in face-to-face position may very easily be effected in the manual operation of setting up the carton since the openings 20 and 21 are sufficiently large to permit an operator's fingers to pass into the carton to press the respective tongues into the desired locked position. However, it is by no means necessary that care be exercised to make sure that the tongues are locked in this manner since the end ears of the respective locking tongues will effectively serve to prevent unlocking of the flaps whether or not they are folded in any degree toward the flat face-to-face position illustrated in Fig. 7. When bottled or other goods are packaged in the carton, the goods will usually force these locking tongues into face-to-face position as shown in Fig. 7 wherein the outline of bottled goods is indicated in dotted lines, and from which it can be seen that said goods are capable of automatically completing the folding of said locking tongues to the face-to-face condition illustrated in Fig. 7.

In setting up the carton and forming the bottom, the manual operations are such that the operator usually completes the closing of the bottom holding the carton within his thumbs on the bottom and with two or three of his fingers of each hand passing through the respective openings 20 and 21 and pressing the locking tabs 14 and 15 toward their fully locked position as illustrated in Fig. 7. It is very convenient with such a grip on the carton to turn it upright and

set it down on a worktable or the like ready for filling. The carton then is of substantially rectangular form having its bottom closed and its top open.

Rectangular flaps 24 and 25 extend from the respective end walls 1 and 2, and rectangular top closing flaps 26 and 27 extend upwardly from the respective side walls 3 and 4. These flaps 24, 25, 26 and 27 are connected to the upper edges of the respective walls through the agency of suitable fold lines as indicated at 28.

All of the flaps 24 to 27 may remain in their normal or initial coplanar relation to the respective walls from which they extend. At some time before the carton is filled, the flaps 24 and 25 are preferably turned down into face-to-face engagement with the inside faces of the respective end walls 1 and 2 as best shown in Fig. 6. This may be done after the carton bottom has been formed, and as a manual operation in the process of setting up and filling the carton. However, it is generally preferred that these flaps 24 and 25 be folded down and adhesively secured in their respective folded positions, by the box maker during the production of the collapsed tubular box blank. It is a relatively simple operation on conventional box-making machinery to fold these flaps to the desired position and to adhesively secure them in such position.

The flaps 24 and 25 having been turned in, the goods to be packaged are introduced. The goods force the locking tongues 14 and 15 downwardly into face-to-face relation to the inside of the carton side walls and hold the tongues in such position whereby the bottom structure is effectively locked against unfolding or opening. Hence it will be seen that the locking ears 14a and 15a are not essential; but they are desirable in that they serve to hold the bottom structure against unfolding pending introduction of the goods into the carton. The goods in the carton also serve to force the ears 3c and 4c toward their normal positions in the planes of the walls 3 and 4 respectively (as shown in Fig. 7) so as to close the openings through which the locking tongues were moved into the carton.

After the carton has been filled, a carrying handle is applied. A wire handle of fairly rigid, but, nevertheless, at least slightly resilient wire is preferred. Such a handle is formed by bending the selected wire to the inverted U-shaped condition shown in Fig. 6, the lower free ends of the side legs of the handle being provided with inwardly and upwardly turned hook formations 30 and 31. Such handle is assembled with the package by first engaging one of its hooked ends 30 and 31 with the upper end of the end wall 1 or 2, preferably engaging the hook with about the middle of the wall near its upper end, and then applying such lateral force on the hook as to cause the engaged end wall to buckle inwardly while at the same time effecting similar buckling of the opposite end wall by hand to permit the other hook end of the handle to be moved downwardly over the central portion of such manually buckled wall. The handle may then be moved downwardly along the middle of the buckled wall portions into predetermined anchored positions.

For handle anchoring purposes, ears or tongues 32 and 33 are provided in the end walls 1 and 2 by means of U-shaped slits and fold lines connecting the free ends of the side legs of the slits. Similar ears or tongues 34 and 35 are formed respectively in the side wall top flaps 24 and 25. When the top flaps 24 and 25 are folded down on

the inside of the respective walls 1 and 2, the ears 34 and 35 register with the ears 32 and 33, the hinge lines for the registering ears being then so located relative to each other that the registering pairs of ears may be folded inwardly and upwardly so as to form four-ply fold-formed edges 36 and 37, respectively, against which the hooks 30 and 31 of the handle bear.

The handle 29 is moved downwardly with its hooks 30 and 31 pressing against the walls 1 and 2 until said hooks engage said ears 32 and 33. The handle is made of wire (or other material) having sufficient stiffness to cause the registering ear elements to be automatically displaced inwardly and upwardly incident to the pressure exerted by the end portions of the hooks 30 and 31 against said ears, and the resilient outward force exerted by the inwardly buckled portions of the upper portions of the walls 1 and 2, as illustrated. Then, by slight upward movement of the handles, the hooks will effect upward folding of the ears and seating of the hooks on said fold-formed edges 36 and 37. Hence, the operation of applying the handle 29 consists mainly in the simple application of the hooked ends of the legs of the handle over the upper end of the carton, and downward movement of the handle until the hooked ends rest on the registering ears, followed by slight retractive or upward movement of the handle.

Frictional engagement between the inwardly buckled walls 1 and 2 and the legs of the handle will normally maintain the handle in its operative position in which it extends above the top plane of the carton. However, the legs of the handle may have their lower end portions bent outwardly so as to diverge downwardly as best illustrated in Fig. 6. These diverging leg portions rest on the underlying portions of the carton walls which more or less conform to the positions of said handle portions. Downward movement of the handle is therefore resisted by said seating of the diverging leg portions on the correspondingly angled carton wall portions.

To complete the closing of the carton, the top wall flaps 26 and 27 are next folded inwardly, one over the other. Each of these flaps 26 and 27 is provided with suitable slit lines 38 and 39, respectively, of shallow U-shaped form and fold lines 40 and 41, respectively, connecting the free ends of the side legs of the slits 38 and 39. These slits and fold lines form ears 42 and 43, respectively, which may be displaced to provide an opening for permitting passage of the handle through the respective flaps, it being somewhat preferable that the flaps be simply folded inwardly and downwardly with the respective ears being displaced upwardly by the handle. The main lengths of the slits 38 and 39 are so positioned that when the flaps 26 and 27 are in their horizontal closed positions, the handle will project through said slits without significant displacement of the ears. Small holes such as indicated at 44 may be provided in the slits to accommodate the side legs of the handle to thereby effectively avoid any necessary displacement of the material of the ears or flaps.

When the top closure flaps are in closed position, they are more or less automatically locked in that position since they cannot swing upwardly to open position without displacing the ears 42 and 43. The paperboard material usually employed in the production of cartons of this type is usually stiff enough to prevent such ear displacement merely by reason of the tendency of

the flaps to swing upwardly to open position. Hence, the carton remains in effectively closed position while at the same time being capable of being easily opened without destruction or tearing by the application of manual lifting force to the respective top flaps.

When a filled carton such as described is to be packaged in a box or shipping case, the handle 29 may be pushed downwardly until its horizontal upper leg rests on the closed upper flap of the package, to thereby eliminate interference by the handle with the packaging of the filled cartons one on top of another.

Incident to the collapsing of the upper portions 15 of the end walls 1 and 2, as described, the upper portions 3a and 4a of the side walls are pulled angularly inwardly as illustrated in Fig. 7. This tends to pull all of the side walls into firm engagement with the adjacent wall portions of bottles packaged in the carton to thereby insure holding of the bottles in tightly packed condition which prevents them from rattling when the package is carried through the agency of its handle.

25 Also incident to the buckling of the flaps 24 and 25 inwardly in connection with the application of the handle to the carton, the lower portions of said flaps diverge inwardly somewhat from the planes of the buckled upper wall portions 1a and 2a so as to project inwardly as shown at 49 in Fig. 6. These inwardly projecting buckled flap portions enter between the adjacent pair of bottles, as will be evident from an inspection of Fig. 6, and may bear against the 30 bottles to thereby aid in holding them firmly against one another to avoid rattling noises from within the carton.

The fold lines 5, 6, 7, and 8 in the walls of the 40 carton serve to more or less control the shaping of the carton incident to the collapsing or inward buckling of the end walls as already described. To further control the shaping of the carton, the upper portions 1a and 2a of said end walls are provided with vertically extending central fold lines 45 and with diverging fold lines 46 and 47 which serve in cooperation with contiguous fold lines to define panel-like sections of predetermined size and shape thereby to avoid irregularities which may occur if haphazard folding were permitted to occur. Inasmuch as the upper end wall flaps 24 and 25 are buckled in conformity with the buckling of the upper wall portions 1a and 2a, these flaps 24 and 25 are also provided with vertical center fold lines 50 which, in the blank shown in Fig. 2, are, in effect, continuations of the fold lines 45.

The described carton construction results in a very rigid paper carton, it being observed that the three-ply bottom construction, when locked in closed position, provides a very rigid structure which effectively holds the carton body in its rectangular position. This three-ply bottom thickness provides an adequate amount of material to take up any moisture which may occur within the carton incident to condensation on a cold bottled product, and also to withstand significant impairment incident to the standing of the filled carton on a wet bottom or shelf of a refrigerator or refrigerating cabinet. Although the construction is very rigid and durable, it does not involve excessive production costs since there is but little waste of material in the cutting of the blank, and no slow or difficult forming operations or other operations requiring special machinery. The mechanical operations

involved in forming the glued-up tubular blank, may readily be performed on more or less standard box-making equipment. Similarly, no special equipment but only ordinary box-cutting die equipment is required for cutting out and creasing the blanks.

Since the carton may readily be reopened without destroying any part of the carton, and the goods removed therefrom without destroying the carton, it may be reused a number of times, which is an important economic factor. The carton provides a convenient means for returning empty bottles to the dealer so that a large percentage of the cartons will find their way back to the source of the goods for which the carton is designed.

The carton provides complete enclosure for the goods, and it provides a large amount of flat wall area which may be employed for ornamentation or advertising purposes, or the like, if desired.

Various changes may be made in the structure while retaining the principles of the invention.

I claim:

1. A carton structure of the class described, comprising opposed pairs of walls foldably interconnected so as to form a tubular carton body which is foldable to flat, collapsed condition by folding on the lines of connection between said walls, a bottom flap extending from the bottom edge of one of the walls of one of said pairs and having at least one side edge disposed closely adjacent to the bottom edge of a wall of the other of said pairs of walls, an outer bottom flap extending from the bottom edge of the side wall opposite to the last-mentioned side wall and foldable into bottom-forming position under said first-mentioned flap, said outer bottom flap having an extension foldable upwardly over the outside of the first mentioned wall of said other pair of walls and a tongue foldably connected to said extension, said first mentioned wall of said other pair of walls being provided with an opening through which said tongue is movable into the interior of the carton body, said tongue being foldable downwardly within the carton and being of such vertical dimension that its lower end portion is insertable between said first-mentioned flap edge and the adjacent side wall to thereby lock said tongue in said downwardly folded position whereby said outer bottom flap is locked in end wall position.

2. A carton structure according to claim 1 in which the locking tongue is provided with ears extending from its opposite sides, said ears being foldable to laterally extending positions relative to said tongue by engagement with portions of the side wall adjacent the sides of said opening as an incident to the movement of the tongue through said opening, the normal resiliency of the carton material serving to cause said ears to be self-restoring to their normal projecting positions so as to extend beyond the sides of said opening on the inside of the carton to thereby lock said tongue against withdrawal from within the carton and to thereby additionally lock the outer bottom flap in bottom-forming position.

3. A carton of the class described, comprising opposed pairs of walls, foldably interconnected along their side edges so as to form a tubular body which is foldable on the connections between said walls to flat, collapsed condition, the walls of one of said pairs being each provided with an

opening disposed approximately centrally of the width of the wall and adjacent to but spaced upwardly from the bottom edge of the wall, said openings terminating short of the side edges of the respective walls, a pair of bottom-forming flaps foldably connected respectively to the bottom edges of said last-mentioned pair of walls, said flaps having portions respectively extending in opposite directions completely across portions of the carton bottom, each of said flaps being provided with an extension foldable into overlying position on the outside of the wall opposite to the wall from which the flap extends, and with a tongue foldably connected to said extension and insertable through said opening into the interior of the carton, said tongues having ears extending sidewise therefrom beyond the ends of the openings through which said tongues are inserted into the carton to thereby lock said tongues against outward displacement through said openings, said ears being foldable to offset positions to permit passage thereof with said tongues inwardly through said openings, the normal resiliency of the carton material serving to cause said ears to be self-restoring to said locking position, said extensions respectively extending diagonally in opposite directions from portions of the respective bottom-forming flaps so as to locate said tongues substantially centrally of the width of the walls for insertion through said openings as aforesaid.

4. A carton of the class described, comprising a tubular body having opposed pairs of walls, the walls of one of said pairs being each provided with an opening disposed approximately centrally of the width of the wall and adjacent to but spaced upwardly from the bottom edge of the wall, said openings terminating short of the side edges of the respective walls, a pair of bottom-forming flaps foldably connected respectively to the bottom edges of said last-mentioned pair of walls, said flaps having portions respectively extending in opposite directions completely across portions of the carton bottom, each of said flaps being provided with an extension foldable into overlying position on the outside of the wall opposite to the wall from which the flap extends, and with a tongue foldably connected to said extension and insertable through said opening into the interior of the carton, said extensions respectively extending diagonally in opposite directions from portions of the respective bottom-forming flaps so as to locate said tongues substantially centrally of the width of the walls for insertion through said openings as aforesaid.
